UNITED STATES PATENT OFFICE.

MARSHALL TURLEY, OF COUNCIL BLUFFS, IOWA.

IMPROVEMENT IN FELLIES FOR CARRIAGE-WHEELS.

Specification forming part of Letters Patent No. 123,750, dated February 13, 1872.

To all whom it may concern:

Be it known that I, MARSHALL TURLEY, of Council Bluffs, in the county of Pottawattomie and in the State of Iowa, have invented certain new and useful Improvements in Felly for Wagons; and do hereby declare that the following is a full, clear, and exact description thereof, reference being had to the accompanying drawing and to the letters of reference marked thereon making a part of this specification.

The nature of my invention consists in the construction and arrangement of a felly for wheels, as will be hereinafter more fully set forth.

In order to enable others skilled in the art to which my invention appertains to make and use the same, I will now proceed to describe its construction and operation, referring to the annexed drawing, in which—

Figure 1 is a longitudinal vertical section; Fig. 2, a plan view; and Fig. 3 end views of my felly.

A represents the felly, made in the shape of a segment of a circle, of cast-iron, or pressed into shape, of wrought-iron. The felly is hollow or concave, and tapered on both sides toward the center, so that it will run through mud or sand with ease. At one end of the

felly is a projection, *a*, and at the other end is a corresponding groove, *b*, so that the felly may be joined together closely. At suitable intervals on the angle of the felly are boxes or projections *d d*, for the insertion of the spokes *B B*, which pass into wooden blocks *C C* on the inside of the felly. The end of the spoke being split, a wedge, *e*, is driven in, which fastens the spoke securely in place.

Having thus fully described my invention, what I claim as new, and desire to secure by Letters Patent, is—

1. The cast or wrought iron felly *A*, made hollow, with tapering sides, and provided with projection *a*, groove *b*, and boxes *d d*, all substantially as and for the purposes herein set forth.

2. In combination with the cast or wrought iron felly *A*, constructed as described, I claim the spokes *B B*, wooden blocks *C C*, and wedges *e e*, all substantially as and for the purposes herein set forth.

In testimony that I claim the foregoing, I have hereunto set my hand this 24th day of November, 1871.

MARSHALL TURLEY.
